UNITED STATES PATENT OFFICE.

CLARKE P. POND, OF PHILADELPHIA, PENNSYLVANIA.

DOOR-HANDLE.

1,305,619.

Specification of Letters Patent. Patented June 3, 1919.

Application filed March 27, 1917. Serial No. 157,754.

To all whom it may concern:

Be it known that I, CLARKE P. POND, a citizen of the United States, residing in Philadelphia, Pennsylvania, have invented 5 Door-Handles, of which the following is a specification.

One object of my invention is to provide a novel form of door handle particularly designed to prevent the transmission of abnormal or injurious torsional stresses to the lock or latch mechanism actuated thereby, the invention more particularly contemplating a novel form of stop which, after a handle has been turned through an angle 10 sufficient to properly operate the latch or lock, will cause any further turning stress to be transmitted directly from said handle to the door structure without permitting strain of or injury to the spindle on which the 15 handle is mounted or to the latch or lock mechanism.

These objects and other advantageous ends I secure as hereinafter set forth, reference being had to the accompanying drawings, 20 in which,

Figure 1 is a side elevation of a door latch and lock, showing a handle connected thereto in accordance with my invention;

Fig. 2 is a fragmentary section taken 30 through the handle and a portion of the door structure on the line 2—2, Fig. 1; and

Figs. 3 and 4 are perspective views illustrating the preferred construction of the handle and the coöperating portion of the 35 door structure, in accordance with my invention.

In the above drawings 1—1^a represents the two face plates of a metal door which is provided with a latch or lock casing 2. This 40 latter may be equipped with any desired locking mechanism and has a latch bolt 3 connected to be actuated by a square section spindle 4 which projects at opposite sides of the door and is designed for the reception 45 of handles whereby it may be turned at will to withdraw the normally projected latch bolt 3.

In the present case I rigidly fix to each of the external faces of the door plates 1 and 50 1^a an abutment plate 5 which is shown as held in position by relatively heavy screws 6, and is substantially concentric with the spindle 4. Each handle 7 has the form of a bar projecting parallel with the outer surface 55 of the door and is provided with a

head portion 8 into which the spindle 4 passes and to which it is held by a pin 9. This head is so formed as to space the handle 7 away from the surface of the door and adjacent the latter it is expanded to substantially the diameter of the plate 5 to form a casing 10.

Within this expanded or casing portion are a pair of integral oppositely placed lugs 11 designed to coöperate with abutments 12 forming a part of a projection from the outer face of the plate 5, and the coacting faces of these two sets of abutments are preferably formed to lie in planes radial of the spindle 4; it being noted that the angular length of each of the recesses partially defined by each pair of the faces 13—13 is greater than the angular length of the lug 11 of the handle which operates within it, so that said handle may be turned through a certain angle without interference from said abutments.

The parts are so proportioned that this permissible angular movement of the handle 11 is sufficient to properly operate the latch 80 bolt 3 and if it be attempted to turn said handle further, its abutments 11 engage the shoulders or faces 13 of the abutments 12, thereby transmitting to the door structure the force applied to turn said handle. The 85 spindle 4 is thus relieved of stress after it has been turned sufficiently to draw in or operate the latch bolt and there is consequently no danger of injury either to said spindle or to the mechanism connected therewith.

While in the foregoing description and in the claims I have referred to a latch as the device which is actuated by the handle, it is to be understood that any other desired 95 form of door holding or retaining device which includes one or more elements which it is desired to protect from abnormal stresses transmitted from the handle, may be substituted for such latch without departing 100 from my invention.

I claim;

1. The combination of a door; a bolt therefor; mechanism for actuating the bolt including a rotary spindle; at least one abutment mounted on the door; a handle fixed to the spindle and having a portion inclosing said abutment; with a second abutment on the inclosing portion of the handle mounted to engage the abutment on the door 110

after the handle with the spindle has been turned through a predetermined angle.

2. The combination of a door; a bolt therefor; mechanism for actuating the bolt including a rotary spindle; a plate on the door adjacent said spindle and having opposite abutments; a handle fixed to the

spindle and including a flange extending over said abutments on the plate; with abutments on said flange placed to coöperate with said abutments on the plate to limit the rotation of the handle with said spindle.

In witness whereof I affix my signature.

CLARKE P. POND.
